UNITED STATES PATENT OFFICE

HARRY WACHENHEIMER, OF PROVIDENCE, RHODE ISLAND

CLASP

Application filed June 11, 1931. Serial No. 543,662.

The present invention relates to a clasp or clasp-connector and, although primarily intended as a connector for the free ends of a string of pearls or other stones or gems, is suitable as a connector for the free ends of other necklaces, bracelets, and similar articles of jewelry for personal wear.

The principal object of the invention is to provide a clasp of novel construction in which the use of solder is eliminated and in which auxiliary springs are obviated.

Another object of the invention is to produce a clasp which is simple in construction and inexpensive to manufacture, and which is composed of a minimum number of parts.

A further object of the invention is generally to improve the construction of a clasp-connector.

To these ends the invention consists of the novel construction and arrangement of parts hereinafter described and more particularly set forth in the claims. In describing the invention in detail reference will be made to the accompanying drawing, in which:

Fig. 1 is a view showing the clasp connected to the rings at the free ends of a necklace, such as a string of pearls;

Fig. 2 is a side view of the clasp, partly in elevation and partly in section;

Fig. 3 is a transverse sectional view of the clasp illustrating the pivotal connection;

Fig. 4 is a view similar to Fig. 3 of a modified form;

Fig. 5 is a view of the blank from which one part of the connector is formed.

A necklace, such as a string of pearls, usually has at its free ends rings like those designated by the reference character 10, in Fig. 1.

According to the present invention these rings are connected by the clasp 11, shown more clearly in Fig. 2, whereby either one or both rings of the necklace may be released from the clasp at either one or at both ends thereof.

Said clasp 11 comprises a channel member having spaced side walls 12, 13 and a bottom wall 14 which projects at ends 15, 15 longitudinally beyond the ends of the side walls. Said projections 15, 15 have up-turned lips 16, 16 at the free ends thereof. This channel

member is formed from the sheet metal blank shown in Fig. 5 in which 12a, 13a designates the portions which form the side walls 12 and 13, and in which 14a designates the part from which the bottom wall 14 is formed, the parts 12a and 13a being bent upwardly above the dotted lines to the position shown more clearly in Figs. 3 and 4. The parts 12a and 13a have aligned apertures 19 within which pintles or pivot pins are mounted as will presently appear.

Said clasp also comprises closure members 17, 17, which are pivotally mounted in said channel member between the side walls 12 and 13. As shown in Fig. 3, the closure members have pivot pins 18, 18 which are mounted in pairs of aligned apertures 19, 19 in the side walls of the channel member. As shown in Fig. 4, the pivotal connections between the members 17, 17 are constituted by separate pintles 20 which are seated in said apertures 19, 19 and on which the ends of the members 17, 17 are pivotally mounted. The closure members 17, 17 have forwardly projecting portions extending over the bottom wall 14 beyond the ends of the side walls 12, 13 of the channel member and are spaced from the bottom wall of said channel member whereby the rings 10 can be positioned and releasably secured between said bottom wall and the forwardly projecting portions of the closure members. Said members 17, 17 have downturned lips 21, 21 which engage the lips 16, 16 in overlapping relation, said engagement consisting of a tight sliding fit afforded by the construction shown and by the resiliency of the metal so that these parts, although readily releasable when desired, are normally in comparatively secure engagement whereby to prevent accidental unfastening of the clasp. The lips 21, 21 are provided with small knobs 22, 22 which facilitate moving the closure members 17, 17 to open position. To provide for adjusting the length of a necklace, bracelet, or similar article, the clasp is provided with transverse ribs 23, 23 extending across the bottom projections 15, 15 about half way between the free ends of the latter and the ends of the side walls, forming two ring fastening posi-

tions 24 and 25 at each end of the clasp. Preferably, as shown, the closure members 17, 17 have similar ribs 26, 26 which overlie the ribs 23, 23, and cooperate with the latter to retain the rings 10 in position. The closure members 17 may be provided with cavities which may receive gems or other ornamentation and the clasp may be enamelled and otherwise ornamented as desired. The several parts of the clasp may be struck from sheet metal and bent into form or can be struck out into shape by suitable dies as will be obvious to those skilled in the art. I therefore reserve the right to all such changes in the arrangement, assembly, construction and ornamentation as will readily occur to those skilled in the art, and I do not wish to be limited to the embodiment illustrated except as required by the appended claims and the prior art.

Having thus described my invention, what I claim and desire to secure by Letters Patent of the United States is:

1. A clasp comprising a channel member having a pair of spaced side walls and a bottom member projecting beyond both ends of said side walls, the free ends of said bottom member having upwardly projecting portions, and two closure members pivotally mounted in said channel member between said side walls, the ends of said side walls terminating substantially at the points of pivotal connection of said closure members, one of said closure members having a portion projecting beyond one end of said side walls over the bottom member, and the other closure member having a portion projecting beyond the other end of said side walls over the bottom member, the free ends of said closure members having downwardly projecting portions releasably engaging said upwardly projecting portions with a tight sliding fit, said portions of the closure members projecting beyond the side walls of the channel member being spaced from the bottom member whereby rings or the like can be positioned and releasably secured between said bottom and closure members.

2. A clasp comprising a channel member having a pair of spaced side walls and a bottom which projects beyond said side walls longitudinally thereof, said side walls having aligned apertures, and a closure member having lateral pivot pins mounted in said apertures for pivotally connecting said closure member in said channel member, and a lip on said closure member releasably engaging the projecting end of the bottom of said channel with a tight sliding fit, said projecting portion of said bottom having a transverse rib positioned between the end of said projection and the adjacent ends of said side walls.

3. A clasp comprising a channel member having a pair of spaced side walls and a bot-

tom which projects beyond said side walls longitudinally thereof, said side walls having aligned apertures, and a closure member having lateral pivot pins mounted in said apertures for pivotally connecting said closure member in said channel member, and a lip on said closure member releasably engaging the projecting end of the bottom of said channel with a tight sliding fit, said projecting portion of said bottom having a transverse rib positioned between the end of said projection and the adjacent ends of said side walls, and said closure member having a transverse rib overlying the rib on said bottom member.

In testimony whereof I hereunto affix my signature.

HARRY WACHENHEIMER.
